CLAIM

The ornamental design for an apparatus for treating body tissue sphincter, as shown and described.

DESCRIPTION

FIG. 1 is a top perspective view of an apparatus for treating body tissue sphincter, showing our new design;

FIG. 2 is a front elevational view thereof;

FIG. 3 is a back elevational view thereof;

FIG. 4 is a left elevational view thereof;

FIG. 5 is a right elevational view thereof;

FIG. 6 is a top plan view thereof; and,

FIG. 7 is a bottom plan view thereof.
